CLAIM

I claim the ornamental design for an extended, armored glove, as shown and described.

DESCRIPTION

FIG. 1 is a top perspective view of an extended, armored glove, as worn by a user, according to the present design; FIG. 2 is a bottom perspective view thereof; FIG. 3 is a front elevation view thereof; FIG. 4 is a rear elevation view thereof; FIG. 5 is a right-side elevation view thereof; FIG. 6 is a left-side elevation view thereof; FIG. 7 is a top plan view thereof; and, FIG. 8 is a bottom plan view thereof.

The dash-dash broken lines shown in the drawings represent conventional stitching and are a part of the claim. The dot-dash-dot broken lines depict the wrist strap and form no part of the claimed design.
